UNITED STATES PATENT OFFICE.

WILLIAM R. COCHRAN, JR., OF DELPHOS, OHIO, ASSIGNOR OF ONE-HALF
TO THOMAS J. EDWARDS, OF LIMA, OHIO.

DERAILER FOR RAILWAYS.

No. 838,083.

Specification of Letters Patent.

Patented Dec. 11, 1906.

Application filed May 9, 1906. Serial No. 316,013.

To all whom it may concern:

Be it known that I, WILLIAM R. COCHRAN, Jr., a resident of Delphos, in the county of Allen and State of Ohio, have invented certain new and useful Improvements in Derailers for Railways; and I do hereby declare the following to be a full, clear, and exact description of the invention, such as will enable others skilled in the art to which it appertains to make and use the same.

My invention relates to an improvement in derailers for railways, the object of the invention being to provide improvements of this character of extremely simple construction, cheap to manufacture, strong and durable in use, and which absolutely prevents a train passing from a siding onto the main track when the main track is open.

A further object is to provide improvements of this character which permit a train to pass onto the siding after the switch-points are thrown, but automatically sets to prevent any return of the train until the switch is opened.

With these and other objects in view the invention consists in certain novel features of construction and combinations and arrangements of parts, as will be more fully hereinafter described, and pointed out in the claims.

In the accompanying drawings, Figure 1 is a plan view illustrating my improvements. Fig. 2 is a view in section on the line *x x* thereof, and Figs. 3 and 4 are detail views.

1 represents the outside rail of a siding, and 2 my improved derailler, which is located some distance from the switch, as is customary.

The derailler comprises two main parts—namely, the derailler proper, 2, and its support or carrier 3. The support or carrier 3 has a small platform 4 and an outward extension 5. The platform 4 is secured to an arm 6, which latter and an arm or extension 7 on the derailler are pivotally secured, as shown, permitting both to move together or the derailler to move independently, as will hereinafter appear. The derailler rests on platform 4 and is recessed to receive the rail 1 and project its top portion over the rail, forming a tread portion 8, onto which the wheel-tread rides, elevating the wheel-flange onto the derailler, the latter being dished, as shown at 9,

to prevent the wheel-flange violently striking the same and permitting it to ride easily onto the derailler and move against a cam or diagonal flange or web 10 on the derailler and be guided thereby off the rail. 55

The derailler is provided with a rod 11, secured thereto and movable in a perforated lug 12 at the outer end of extension 5, and a coiled spring 13 is located on this rod between the lug 12 and the derailler to normally hold the latter on platform 4, a lug 14 being provided on derailler 3 to compel the derailler to 60 move back from the rail when the platform 4 is moved.

A link 15 connects the arm 6 with the switch-throwing mechanism, (not shown,) so that when the switch is thrown the derailler will also be moved, as will now be explained. 70

The operation of my improvements is as follows: The derailler is maintained in the position shown in Fig. 1 and is moved only 75 when the switch is thrown to open the siding. As the train passes from the main track onto the siding the switch is of course held open; but after the last car has passed the switch the siding is closed when the last car is some 80 distance from the derailler, and the latter will be moved over the rail when the switch is thrown. However, this will not interfere with the rear end of the train passing onto the siding, as the wheel-flanges will engage 85 the arm 7 and force the derailler back against the tension of spring 13, which latter will return the derailler to normal position over the rail. Any movement of the train toward the main track before the switch is open will 90 cause the wheel-treads to ride on the tread portion 8 of the derailler, which will guide the wheel-flanges against the cam-web 10 and derail the car. It will thus be seen that while the wheels can pass the derailler when 95 moving onto the siding even though the switch be closed the wheels cannot pass to the main track until the switch is open, and my improvements are an absolute preventative for accidents due to this cause. 100

A great many slight changes might be made in the general form and arrangement of parts described without departing from my invention, and hence I would have it understood that I do not restrict myself to the 105 precise details set forth, but consider myself

at liberty to make such slight changes and alterations as fairly fall within the spirit and scope of my invention.

Having fully described my invention, what

5 I claim as new, and desire to secure by Letters Patent, is—

1. The combination with a movable support, of a derailer movable on the support, means for moving the support to move the 10 derailer away from rail, and said derailer constructed to be moved independently of the support, by a wheel passing in one direction but derail the wheel in passing in the opposite direction.

15 2. The combination with a rail, of a derailer, an arm thereon pivotally secured to one side of the rail permitting the derailer to be moved by a wheel-flange engaging the arm, a tread portion on the derailer supported 20 on the rail, a deflecting flange or web on the derailer to be engaged by a wheel-flange when the wheel rides up on the tread and deflect the wheel from the track, and a recess 25 between the tread portion and flange to permit the wheel-flange to ride onto the derailer without violently striking the same.

3. The combination with a rail, of a platform, an extension thereon, a pivoted arm secured to the platform, a derailer, an arm 30 thereon pivotally secured to the pivotal end

of the platform-arm, a rod on the derailer movable in a lug on the extension, a spring on the rod bearing against the derailer, and a lug on the derailer to engage the platform.

4. The combination with a rail, a movable 35 platform, means for connecting the platform with a switch-throwing device to lock the platform against movement when the switch is thrown, of a derailer mounted to move on the platform and constructed to be moved 40 by the flange of a wheel in passing in one direction and to derail the wheel when passing in the reverse direction, and elastic devices normally holding the derailer over the rail.

5. A derailer, having a pivoted arm made 45 with a cam edge to be engaged by a wheel-flange to move the derailer out of the path of a wheel when the wheel is moving in one direction, a tread on the derailer supported on the rail to receive the wheel and elevate the 50 flange of the wheel, and a cam flange or web on the derailer to be engaged by the wheel-flange to deflect the same from the rail.

In testimony whereof I have signed this specification in the presence of two subscribing witnesses.

WILLIAM R. COCHRAN, JR.
